CLAIM

The ornamental design for a corner shelving assembly, as shown and described.

DESCRIPTION

FIG. 1 is a top and front perspective view of a corner shelving assembly showing our new design, with the broken-line disclosure of a pole on which the shelves are mounted being for illustrative purposes only and forming no part of the claimed design;

FIG. 2 is an enlarged left and front elevational view thereof, the view from the right and front being a mirror image of that shown;

FIG. 3 is an enlarged left and rear elevational view thereof, the view from the right and rear being a mirror image of that shown;

FIG. 4 is a top and front perspective view thereof, with the broken-line disclosure of wall-mounting means being for illustrative purposes only and forming no part of the claimed design;

FIG. 5 is an enlarged left and front elevational view thereof, the view from the right and front being a mirror image of that shown;

FIG. 6 is an enlarged left and rear elevational view thereof, the view from the right and rear being a mirror image of that shown;

FIG. 7 is a top plan view thereof, with the broken-line disclosure of a pole on which the shelves are mounted being for illustrative purposes only and forming no part of the claimed design; and,

FIG. 8 is a top plan view thereof, with the broken-line disclosure of wall-mounting means for illustrative purposes only and forming no part of the claimed design.
